UNITED STATES PATENT OFFICE.

ALBERT EDWARD JONES, OF FIUME, AUSTRIA-HUNGARY.

GYROSCOPIC STEERING DEVICE FOR TORPEDOES.

1,173,435.

Specification of Letters Patent. Patented Feb. 29, 1916.

Application filed August 19, 1913. Serial No. 785,456.

To all whom it may concern:

Be it known that I, ALBERT EDWARD JONES, subject of the King of Hungary, residing at Fiume, in the Empire of Austria-Hungary, have invented certain new and useful Improvements in Gyroscopic Steering Devices for Torpedoes, of which the following is a specification, reference being had therein to the accompanying drawing.

10 The present invention relates to steering regulators for torpedoes of the kind in which the centrifugal mass is driven by compressed air, which by means of accurately adjustable timed locking devices 15 (see E. P. 19987 A. D. 1908 and U. S. P. 954634) is allowed to act upon the centrifugal mass during a definite phase of the launching and in which the motor action of the compressed air upon the 20 centrifugal mass is caused to cease owing to the fact that at a given moment the access of the compressed air to the fly wheel is cut off.

The present invention provides the improvement that for the purpose of more exactly cutting off the motor effect of the compressed air, the latter does not act directly upon the fly wheel, but a separate turbine is provided whose shaft is clutched 30 to the shaft of the centrifugal mass, and the motor effect of the compressed air is cut off owing to the fact that the clutch interposed between the turbine shaft and the fly wheel shaft is thrown out at the 35 proper moment. The clutch interposed between the rigid horizontally mounted turbine shaft and the horizontal shaft of the centrifugal mass, at the same time serves as a retaining member, which during the 40 driving period holds the gyroscope shaft in the normal position, for which purpose a special part has been provided in the constructions hitherto adopted. The arrangement described therefore not only renders 45 unnecessary the employment of a special retaining member, but owing to the identity of the clutching and unclutching member with that by which the gyroscope is retained in the normal position, the effect is 50 obtained that the point of time at which the motive power is cut off absolutely coincides with the time at which the gyroscopic system is released, a factor which is of the greatest importance for insuring 55 precision in the gyroscopic action.

The accompanying drawing (Figure 1)

represents a steering regulator embodying the invention in partial vertical longitudinal section through the axis of the flywheel. Figs. 2 and 3 are cross-sections on the lines 60 C D and A B in Fig. 1. Fig. 4 shows the clutch thrown out in a view analogous to Fig. 1.

The centrifugal mass *o* is keyed upon a horizontal shaft *a* mounted in the known 65 manner in the annular system *m*, *n*; the left hand end of this shaft (Fig. 1) passes through the ball bearing *m'* on the horizontal ring *m* and terminates in a claw 70 clutch 11.

In line with the normally arranged horizontal shaft *a* of the centrifugal mass *o* a short hollow shaft *r* is mounted; this shaft is fitted with an air turbine *v* surrounded by a rigid ring *w* provided with 75 a plurality of discharge nozzles *p* (Figs. 1 and 3). In this hollow shaft *r* a shaft *b* is rotatably guided, and this shaft *b* upon its end directed toward the gyroscopic system is provided with a clutch element 80 12 corresponding with the clutch element 11. This shaft *b* is also guided in a rigid tubular socket *z* and carries two collars 85 4, 4 engaged by the crank pin 5 of a bent adjusting lever *g*, *k* which by means of a resilient trip device of known construction is moved into, and retained in the positions shown in Figs. 1 and 2. This trip device consists of a pin 10 guided in a rockable 90 eye 7 and pivoted to the upwardly directed 95 arm *k* of the bent lever *g*, *k* pressed downward by a spring 8 interposed between the eye 7 and the head of the pin 10, its stroke being limited by the nut 13.

In the position illustrated in Fig. 1 the 95 clutch 11, 12 arranged between the displaceable part *b* of the turbine shaft and the gyroscope shaft *a* is thrown in and the rotation imparted to the turbine wheel *v* during the air admission period is transmitted to 100 the centrifugal mass of the gyroscope. If, however, the bent lever *g*, *k* is shifted from the position illustrated in Fig. 1 to the end position shown in Fig. 4, the shaft *b* rotatably guided in the turbine shaft *z* is pressed 105 back thereby throwing out the claw clutch between the turbine wheel and the gyroscope.

The rotation of the bell-crank lever *g*, *k* which throws the displaceable turbine shaft *b* in and out of gear, is produced by a bolt *t* 110 rigidly guided upon the casing and between whose two driver tappets 2, 3 the end of the

arm *g* engages. The bolt *t* is actuated by a bell-crank lever *h* mounted upon the casing and subjected on the one hand to the influence of the differential piston *u* acted 5 upon by a timed locking device and on the other hand to the influence of the counter spring *14* acting upon the rod *16*, in such a manner that the spring pressure brings the bell-crank lever into that position (Fig. 1) 10 in which the turbine *v* is clutched to the centrifugal mass *o*, while by the outwardly directed movement of the differential piston (arrow 1, Fig. 2) the turbine and the fly-wheel shaft are unclutched. 15 By means of the bell-crank lever *h*, which is provided with an extension serving as a handle, the members transferring the gyroscopic system into the normal position are thrown in and out of gear in the known 20 manner and by the displacement of the differential piston in the direction indicated by the arrow the conduit leading to the turbine is closed. Accordingly the differential piston *u* which is subjected to the influence of the 25 timed locking device does not throw-out the drive of the gyroscope shaft by cutting off the compressed air supply as in the devices hitherto adopted, but by releasing the clutch between the shaft of a separate driving tur- 30 bine and the shaft of the centrifugal mass.

Having now particularly described and ascertained the nature of my said invention, and in what manner the same is to be performed, I declare that what I claim is:

35 1. In a gyroscope steering device for tor-
pedoes, the combination with a main shaft,
of a fly-wheel keyed on said main shaft, a
clutch-member carried at one end of said
main shaft, a turbine, a turbine shaft alin-

ing with said main shaft, a movable clutch- 40 member carried on said turbine shaft and adapted to engage the clutch-member on said main shaft, and a differential control mechanism for clutching and unclutching said turbine shaft from said main shaft. 45

2. In a gyroscope steering device for tor-
pedoes, the combination with a main shaft,
of a fly-wheel keyed on said main shaft, a 50 clutch-member carried at one end of said
main shaft, a turbine, a turbine shaft alin- 55 ging with said main shaft, a movable clutch-
member carried on said turbine shaft and
adapted to engage the clutch-member on
said main shaft, and a control mechanism
comprising a pivotally supported bell-crank 60 lever, a rod pivotally connected to the long
arm of said bell-crank lever, a spring car-
ried by said rod and acting to oppose the
movement of said bell-crank lever in one di-
rection, a pivoted bolt depending from said 65 bell-crank lever, tappets arranged on one
side of said bolt and adjacent the lower end
thereof, a trip-lever fulcrumed below said
turbine shaft and having one of its arms
connected to said movable clutch-member 70 and the other of its arms operating between
said tappets of said bolt, and a differential
piston for actuating said bell-crank lever in
one direction, and against the tension of said
spring, whereby the turbine shaft may be
alternately clutched to or unclutched from
said main shaft.

In testimony whereof I affix my signature
in the presence of two witnesses.

ALBERT EDWARD JONES.
